UNITED STATES PATENT OFFICE.

CLARENCE S. JOHNSTON, OF GLENDALE, MONTANA.

OIL CAN.

1,418,576.

Specification of Letters Patent. Patented June 6, 1922.

Application filed April 12, 1919. Serial No. 289,557.

To all whom it may concern:

Be it known that I, CLARENCE S. JOHNSTON, a citizen of the United States, residing at Glendale, in the county of Dawson and State 5 of Montana, have invented a new and useful Oil Can, of which the following is a specification.

This invention relates to improvements in oil cans, one object of the invention being 10 the provision of a can for lubricating machinery and the like, and provided with means, where at pleasure the desired quantity of oil may be ejected through the spout.

A further object of this invention is the 15 provision of an oil can having mounted therein a novel form of pump operable exteriorly and at a convenient point for manipulation, so that oil may be ejected from the can through the spout by merely depressing the pump, which automatically returns 20 when released.

A still further object of this invention is the provision of an oil can which is simple, durable and inexpensive in construction, and 25 thoroughly efficient and practical in use.

With the foregoing and other objects in view and which will appear as the description proceeds, my invention resides in the combination and arrangement of parts hereinafter set forth and particularly pointed out in the claims, the scope of the invention being limited however only by what is claimed.

In the accompanying drawings:—

Figure 1 is a view partly in elevation and section of an oil can made according to and embodying my invention.

Figure 2 is a section taken on line 2—2 of Figure 1.

Referring to the drawings, the numeral 5 designates the body or receptacle of the can having the solid portion 6 of the spout carried thereby, the flexible portion 7 being in communication therewith and provided with 45 the solid outlet end 8.

Mounted within the body upon the center of the bottom thereof, is the lower cup member of the pump, which is in communication with the lower end of the solid portion 6 of 50 the spout. The upper inverted cup member 10 of the pump is of slightly less diameter than the member 9, so that when the same is depressed, as will presently appear it will telescope within the member 9, and cause the 55 oil which normally enters the member 9 as

indicated by the arrows to be ejected through the spout. A spring 11 surrounds the stem 12, which is carried by the member 9 and has mounted thereon slidably the member 10, so that the member 10 is normally held 60 in the position as shown and thus provides the oil inlet 13 between the two members 9 and 10.

The rod 14 is operably connected to the top of the member 10 and extends through 65 the removable filling cap 15, and carries the manipulating button 16, which is thus in ready access to the thumb of the operator when holding the can by its handle. A spring bracket 17 is attached to the inner 70 wall of the can and to the member 10, to assist in the return of the member 10 and also the steadyng of the same in its reciprocatory movement.

This may be dispensed with, however, but 75 in view of the fact that the rod 14 is slightly inclined, it is thought that a more durable construction will be produced.

What I claim, as new, is:—

1. An oil can including a body having a 80 bottom, a cup member fixedly mounted on said bottom and in the body, an outlet spout integral with said member and extending along the outer side of the body, an inverted cup member of less diameter than and adapted 85 to move downwardly into the first named cup member, a spring bracket secured within the body for yieldingly supporting the inverted cup member, a spacing spring interposed between and housed within the two 90 cup members, and means extending upwardly through the top of the body for depressing the inverted cup member to force it into the other cup member and expel a portion of the contents of the body through the spout, 95 the two cup members being normally spaced apart to provide an annular inlet to the cup members.

2. An oil can including a body, a cup member fixedly mounted on the bottom of 100 said body, a rigid outlet spout extending from the cup member and through an opening in the wall of the body and thence along the outer side of the body, an inverted cup member of less diameter than and adapted 105 to move downwardly into the first named cup member, a spring bracket secured within the body for yieldingly supporting the inverted cup member, a spacing spring interposed between and housed within the two 110

cup members, and means extending upwardly through the top of the body for depressing the inverted cup member to force it into the other cup member and expel a portion of the 5 contents of the body through the spout, the two cup members being normally spaced apart to provide an annular inlet to the cup members.

In testimony that I claim the foregoing as my own, I have hereto affixed my signature 10 in the presence of two witnesses.

CLARENCE S. JOHNSTON.
